ABSTRACT

A circuit interrupter is provided with a parallel-connected resistor which is cooled to a temperature of from 4° K to 80° K, but higher than the critical temperature of the resistance material. The resistor is connected in parallel with the circuit interrupter contacts at either an arbitrary time or just prior to a current zero value. The heating of the resistor during current-limiting operation increases its resistivity by about 100 times.

CURRENT-LIMITING SWITCH EMPLOYING LOW TEMPERATURE RESISTOR

RELATED APPLICATIONS

This application is a division of my copending application Ser. No. 39,040, now U.S. Pat. No. 3,617,807, filed May 20, 1970, entitled CURRENT-LIMITING SWITCH EMPLOYING LOW TEMPERATURE RESISTOR, and assigned to the assignee of the present invention.

BACKGROUND OF THE INVENTION

This invention relates to circuit interrupters, and more specifically relates to circuit interrupters in which a current-limiting resistance having a positive temperature coefficient of resistance is inserted into the circuit being protected during interruption of the circuit.

The use of current-limiting resistors which are inserted into a circuit to limit the current to be interrupted are well known, where such resistors can be inserted in the vicinity of a current zero in the circuit to be interrupted. Such resistors have been inserted into the circuit and their value increased as by a sliding contact arrangement which gradually inserts additional resistance to limit the current to be interrupted. These resistors have also been made of a material which has a high positive temperature coefficient of resistance, so that their resistance will automatically increase due to the heat generated in the resistor when the resistor is inserted in the circuit, thereby reducing or limiting the current in the circuit to be interrupted. Chemically pure iron has been used for such resistors and these resistors will exhibit an increase in resistance of about 12 times. For all other materials known to me the increase in resistance is less than for the pure iron as noted above. U.S. Pat. No. 3,495,056 illustrates an interrupter using a pure iron resistor where the resistor is heated from room temperature to a calculated temperature which the resistor can safely withstand during current-limiting operation.

The principle of the present invention is to cool the resistor which is to be inserted into a circuit which is to be interrupted to a temperature of from 4° K to 80° K, but above the critical temperature at which the resistor material becomes superconductive and to heat this resistor to a temperature of about 373° K during current-limiting operation. By starting with the above low temperature for the resistor, it has been found, unexpectedly, that the resistivity of the material changes, depending on the resistor material, with about the third power of the absolute temperature of the resistor. In particular, when changing temperature from 20° K to 373° K, the resistivity of a pure iron resistor increased by more than 100 times, although the presently expected linear change in resistivity would anticipate only a several-fold change in resistance.

More specifically, it was commonly thought that change in resistivity is given by a linear relationship of the form:

$$\rho = \rho_0 [1 + \alpha(T - T_0)]$$

where ρ is resistivity at temperature T , ρ_0 is resistivity at 0° C and α is the temperature coefficient of the material, typically from 4×10^{-3} to 6×10^{-3} per degree.

The present invention is based, in part, on the discovery that the above-noted expression is followed only for temperatures down to about -70° C. Below -70° C,

however, the resistivity changes according to a different and non-linear relationship which is:

$$\rho = \rho_0 (T/T_0)^\sim$$

where T_0 is 273° K and $\sim$ is a constant depending on the nature of the material used. For example, for tungsten $\sim$ is about equal to three.

The second discovery leading to the present invention is that the specific heat c' decreases below -70° C with the square of the absolute temperature, and, at very low temperatures, with the third power of absolute temperature.

It was further found, in accordance with the invention, that at low temperature the following relation holds:

$$c'/\rho \cdot T = K$$

where K is a constant having a characteristic value for different materials. This constant and the relationship above permits the calculation for a resistor for a given application as will be later described. Typical values for the constant K are approximately as follows:

$$\text{Tungsten: } K \approx 0.15 \times 10^9$$

$$\text{Iron: } K \approx 0.09 \times 10^9$$

$$\text{Copper: } K \approx 0.52 \times 10^9$$

It can be shown that the absolute temperature T reached by the resistor after a time t is:

$$T = T_0 e^{\frac{1}{K} \int_0^t S^2 dt}$$

where S is the current density in the resistor. The resistor should be dimensioned such that

$$\int_0^t S^2 dt$$

reaches the highest possible value during the current-limiting interval in which current flows in the resistor so that the resistor will be heated to its maximum temperature T (and thus undergo a maximum resistance change). If τ is the time permitted for current limiting action, then the resistor should be designed for an effective current density S_{eff} which is:

$$S_{eff} = \sqrt{\frac{1}{\tau} \int_0^\tau S^2 dt}$$

The above integral can then be computed from the predicted wave shape of the current in the resistor and the cross-section of the resistor wire can be computed.

An important aspect of the present invention is that useful current-limiting resistors can be designed despite the low specific heat of the resistance materials at the low initial temperature since the heat produced in the low temperature region is slight. In particular, there is a matching between the specific heat c' and resistivity ρ so that there is a relatively gradual increase in the temperature of the resistor, rather than a rapid increase which could cause an explosive evaporation of the cooling liquid surrounding the resistor.

A few coolants that could be used to cool the resistor are listed in the following table:

Coolant	Boiling Point (°K) at 1 atm.
Nitrogen	77
Neon	27
Hydrogen	20
Helium 4 4	

By varying the pressure, the boiling points can be adapted to specific conditions.

Materials useful for the resistor are preferably extremely pure metals including tungsten, iron and copper.

BRIEF DESCRIPTION OF THE DRAWINGS

FIG. 1 schematically illustrates an interrupter constructed in accordance with the present invention.

FIG. 2 illustrates the operation of the interrupter of FIG. 1 under short-circuit conditions on the line being protected.

FIG. 3 illustrates the operation of the interrupter of FIG. 1 with the contacts being synchronously operated to insert the resistor at a current zero.

FIG. 4 shows an interrupter arrangement which can be synchronously operated as illustrated in FIG. 3.

DESCRIPTION OF PREFERRED EMBODIMENTS

FIG. 1 schematically shows a current-limiter made in accordance with the invention. The current i which is to be reduced or disconnected flows through the closed main switch 1, the auxiliary switch 2 being open for the time being, so that no current flows through the temperature-dependent resistor 3. Thus, the resistor current i_2 is zero. The temperature-dependent resistor 3 is then located in a container 4 which receives the flow of a coolant 6 supplied from a cooling fluid source 5. In order to keep the heat losses as small as possible, the container 4 is surrounded in known manner by a covering 7 which reflects the heat rays. The leads 8 and 9 to the resistor 3 may also be cooled so that the heat loss by thermal conduction is as small as possible. The design of resistor 3 can be determined as follows:

Assume, as shown in FIG. 2, that a short-circuit current i_k with a current slope established by the powerline inductance L occurs at the time $t = -\Delta t$. After the very short time Δt which is a fraction of a millisecond, the auxiliary switch 2 (see FIG. 1) is closed by appropriate operating mechanisms (not shown) and immediately after this, the main switch 1 is opened by the suitable operating mechanisms. When switch 1 opens, there will be arcing across the open switch, which, even in the case of very small spacing of the contacts, exhibit an arc-drop voltage of about 10 V per point of interruption. This arc drop voltage causes the current i_1 to switch into the resistor 3. In this connection, the break current I_T multiplied by the cold resistance r_o of resistor 3 must have a value which is smaller than the total arc voltage U_B . Therefore:

$$I_T r_o = I_T \cdot l \rho_o / q < U_B$$

where l is the length of the resistor wire and q is its cross-sectional area. In the arrangement of FIG. 1, there are two points of interruption so that U_B is about 20 to 30 V. If the arcs are produced in narrow gaps, then voltage gradients of up to several hundred volts per centimeter per point of interruption can be obtained. This may be of importance in particular when

using current limiters in high-voltage direct current systems. The cold resistance r_o thus becomes:

$$r_o \leq U_B / I_T$$

5 In FIG. 1, the peak let-through current i should not be greater than about $(2 - 3) \cdot I_T$. The time τ of flow of current in the case of short-circuit at 50 cycles is about 5 ms and at 60 cycles is about 4.15 ms. Furthermore, since the slope of the current i is known, the 10 course of the reduced current i can be approximately determined. If q in cm^2 is the still unknown cross-section of the variable resistor wire, then by squaring and dividing by q^2 it is possible to calculate the value:

$$S(t) = \int_0^t S^2 dt = \frac{1}{q^2} \int_0^t I^2 dt$$

from the wave shape of the current.

The design conditions are somewhat different in the 20 case of the so-called reduction switch or switch which inserts the variable resistor in the circuit at a current zero. The wave shape of the current i_r which occurs in this type switch is shown in FIG. 3. FIG. 3 shows a short-circuit current i_k in the circuit, and its wave shape 25 if undisturbed by the resistor. Shortly prior to the time current i_k reaches a current zero N , the auxiliary switch 2 is closed and the main switch 1 is opened by means of a suitable synchronous control. The cold resistor r_o , connected in parallel with the main switch 1 is now so 30 dimensioned that the rise of the recovery voltage $(du_w/dt)_o$ is substantially reduced. The value k which is controlling for this is defined by:

$$k = r_o / \sqrt{\frac{L}{c}}$$

For $k \leq 0.5$, the recovery voltage across the open contacts asymptotically approaches the value $\hat{U}$ (see FIG. 3), the slope of the rise with $k = 0.5$ being about $\frac{1}{2}$ that of the unattenuated oscillation.

At $k = 0.1$, the rise of the recovery voltage is reduced to about 10 percent. This extensive reduction of the rise in the voltage now makes it possible dependably to switch extremely high currents into resistor 3 which 45 have correspondingly high slopes $(di/dt)_o$ during passage through current zero since the following relationship is approximated:

$$(di/dt)_o \cdot (du_w/dt) \approx N_o / 2\tau B^2 \text{ constant}$$

50 In the above relation, $N_o = u_B i$ is the steady arc power in the vicinity of the current zero and τ_B is the arc time-constant. Immediately after the current zero N_1 (FIG. 3) the current flows through the cold resistor 3, the resistance of which is thereupon increased by several orders of magnitude so that at the next current zero N_2 the driving voltage u and the very small reduced current i_r pass through zero simultaneously. Therefore, the reduced current i_r can be easily interrupted. Since in the case of the reduction switch, following the techniques of FIG. 3, the energy conversion is much less than in the case of the switch operating, as shown in FIG. 2, the current limiting resistor 3 will be correspondingly smaller and simpler.

60 The following example may serve by way of further explanation of the design of a suitable resistor:

A reductor or switch operating as in FIG. 2 is to be designed for a line-to-line voltage of $U_v = 10,000 \text{ V}$ and

a three-phase short-circuit power P_a of 1,000 MVA. The short-circuit current is $1000\sqrt{3} \cdot 10 = 58$ kA and thus the inductance per phase is $L = 10\sqrt{3} \cdot 58 \cdot \omega \cdot 0.315 \cdot 10^{-3}$ H. The maximum current slope is thus:

$$(di/dt)_o = \frac{\sqrt{2}U_v}{\sqrt{3}L} = \frac{\sqrt{2} \cdot 10,000}{\sqrt{3} \cdot 0.315 \cdot 10^{-3}} = 26 \times 10^6 \text{ A/s}$$

With:

$$\dot{i} = 2.5 \cdot I_T = 10,000 \text{ amp}$$

there is obtained a wave shape of the reduced current i such as shown in FIG. 2. By squaring one obtains $i^2 = f(t)$, from which there follows:

$$S(t) = \int_0^t S^2 dt = \frac{1}{q^2} \int_0^t i^2 dt$$

By planimetry of the i^2 curve one could find:

$$J(1) \approx 7 \cdot 10^4 \text{ (amp}^2\text{sec)}$$

$$J(5) \approx 15 \cdot 10^4 \text{ (amp}^2\text{sec)}$$

For the time $t = 1$ ms, $di/dt = 0$ and thus, taking into consideration a voltage drop of 15 percent:

$$r_1 = u_1/10,000 \approx 7,000/10,000 \cong 0.7 \Omega$$

with $I_T = 4,000$ amp, the cold resistance is:

$$r_o = U_B/I_T = 20/4,000 = 0.005 \Omega$$

$$r_1/r_o = 0.7/0.005 = 140 = \rho_1/\rho_o$$

By linear interpolation one finds the temperature $T_1 \approx 210^\circ\text{K}$ corresponding to P_1 . We must therefore have:

$$T_1 = 40 \cdot e^x = 210; e^x = 210/40 \approx 5.25; x = 1.66.$$

From this there follows:

$$T_1 = 40 \cdot e^{0.67 \cdot 10^{-3} \cdot \frac{1}{q^2} \cdot 7 \cdot 10^4}$$

and thus:

$$q^2 = 0.67 \cdot 10^{-3} \cdot 7 \cdot 10^4 / 1.66 = 2.82 \cdot 10^{-4} \text{ cm}^2$$

$$q = 1.68 \cdot 10^{-2} \text{ cm}^2.$$

The final temperature T_5 is:

$$T_5 = 40 \cdot e^{0.67 \cdot 10^{-3} \frac{15 \cdot 10^4}{2.82 \cdot 10^{-4}}} = 40e^{3.55}$$

$$T_5 = 40 \cdot 34.8 = 1,400^\circ\text{K.}$$

For the length l of the resistor wire there results:

$$l = r_o q/\rho_o = 0.005 \cdot 1.68 \cdot 10^{-2} / 2.25 \cdot 10^{-8} \approx 3,700 \text{ cm} = 37 \text{ m.}$$

The total resistance ratio is:

$$r_s/r_o = \rho_5/\rho_o = 37/0.005 = 7,400.$$

For dependable operation, the variable resistor 3 must have approximately the value r_o at the start of an interruption. This result is obtained by closing the auxiliary switch 2 of FIG. 1 only when the resistor 3 has cooled to a predetermined temperature T_o . In order to obtain short cooling times, the resistor r is preferably made of thin wires or thin strips connected in parallel. With a diameter of the wire of, for instance 0.3 mm, cooling times of fractions of a second can be obtained. The use of thin wires and strips is also advantageous with respect to the skin effect, since the resistivity ρ_o in a cooled condition is very small.

If the interrupter is to be capable of several operations within a very short time interval, it is preferable

to provide at least two circuits in parallel to the main switch 1, each consisting of a resistor 3 and auxiliary switch 2 in series therewith. These circuits are alternately connected whereby the resistor being connected on subsequent operations will have been cooled to the desired low temperature.

One illustrative embodiment of such an arrangement is shown in FIG. 4. In FIG. 4 temperature-dependent resistors 11 and 12 are cooled to a low temperature, as described above. Main interrupter switch 13 is then provided with an electrodynamic drive consisting of a stationary coil 14 and a movable metallic plate 15 which is rigidly connected with the movable bridge contact 16. Auxiliary switches 17 and 18 are provided for resistors 11 and 12, respectively, and are each provided with electrodynamic drives consisting of stationary coils 19 and 20, respectively, and the conductive bridge contacts 21 and 22 which simultaneously serve as secondary coils of their electrodynamic drive system. Movable conductive contact discs 23 and 24 are provided which are connected with the pistons 25 and 26 of the delay pumps 27 and 28. Contacts 23 and 24 are also adapted to be accelerated to the right responsive to energization of coils 19 and 20. The contacts 23 and 24 are connected via a balance beam 29 with a freely movable fulcrum 30 to which a lever 31 is rigidly fastened. Contacts 23 and 24 cooperate with stationary contacts 33-36 and 34-35, respectively. An insulating board, which can be interposed between the contact 33 or contact 34, depending on the position of the pistons 25, 26 respectively, receives lever 31 as shown. Springs 37 and 38 are received in cylinders 27 and 28 and bias the pistons 25 and 26, respectively, to the left. An auxiliary d-c power source is then provided (not shown) which charges capacitor 39. A three-electrode spark gap 40 is then provided in series with a capacitor 39 and can be fired in known manner upon the occurrence of a fault current. Springs 41 and 42 are provided to bias open the auxiliary switches 17 and 18, respectively, so that these contacts will reopen some predetermined time after they are closed by their electrodynamic system.

In order to operate the circuit of FIG. 4 in the mode shown in FIG. 3, the trigger electrode of spark gap 40 is energized from a suitable zero current anticipating circuit 40a, which is suitably coupled to the line being protected, as shown by dotted lines. Circuit 40a may be any conventional type in which an output pulse is generated at some predetermined time prior to a current zero. Note, however, that the circuit of FIG. 4 could be operated outside of the current region, as described in FIG. 2.

The manner of operation of the arrangement is as follows:

In response to an overcurrent and in the vicinity of a current zero, the spark gap 40 fires and the capacitor 39 discharges through coil 14 of the main switch 13 and through coil 20 of the auxiliary switch 18. Auxiliary switch 18 closes and main switch 13 opens, whereby the current i is switched to the resistor 12. The sequence of the closing of the auxiliary switch 18 and of the subsequent opening of the main switch 13 can be controlled by proper design of the movable masses of the switches. With the excitation of the coil 20, the contact 24 is accelerated toward the right and the piston 26 is also pushed to the right in opposition to the spring 38. Auxiliary switch 18 then opens under the in-

fluence of the spring 42 and after a predetermined period of time, whereupon the resistor current is interrupted at the subsequent current zero.

In FIG. 4 assume that an interruption occurred prior to the interruption described above, using resistor 11 and auxiliary switch 17. A second switching operation using resistor 11 is possible only after the resistor 11 has cooled down approximately to the cold value T_0 . This could be done by providing a conventional temperature-measuring device which prevents operation of switch 17 (and switch 18) until the temperature T_0 is reached. However, it is simpler to block the closing of the auxiliary switch during a known cooling time, as measured by conventional means such as a clock or damped pump.

FIG. 4 illustrates a lock-out arrangement for switches 17 and 18 which uses damping pumps. In FIG. 4, after excitation of the coil 20, the auxiliary switch 18 is closed and the piston 26 moves to the right together with the disc 24. The balance beam 29 rotates to a perpendicular position and the lever 31 reaches a horizontal position. During this time, the piston 25 moves toward the left and — since the piston 26 is still approximately in the righthand position — pushes the lever 31 and the insulating disc 32 downward. In this way the contact 23 engages contacts 33, 36, whereby the auxiliary switch 17 is again ready for operation. The closing of the auxiliary switch 18, however, is prevented by the downwardly displaced insulating board 32 so that only auxiliary switch 17 can be actuated upon the next disconnection.

At very low temperatures, but above the critical temperature, the resistivity of resistors is slightly increased by the magnetic field traversing the resistor material. This slight increase in resistance is generally unimportant to the use of the resistors in accordance with the invention. The magnetic field strength can, however, be reduced to harmless values without difficulty by

known magnetic shielding screening.

Although there has been described a preferred embodiment of this novel invention, many variations and modifications will now be apparent to those skilled in the art. Therefore, this invention is to be limited, not by the specific disclosure herein, but only by the appending claims.

The embodiments of the invention in which an exclusive privilege or property is claimed are defined as follows:

1. A current-limiting circuit interrupter comprising, in combination, an electrical resistor made of material having a positive temperature coefficient, means for normally cooling said resistor to a temperature below about 80° K but above the critical temperature at which said material becomes super-conductive, and switching means connected in circuit relation with said resistor for inserting said resistor in a current-carrying circuit, whereby said resistor is heated by the current of said current-carrying circuit and the resistance of said resistor is increased, thereby to limit the current in said circuit, and second switching means; said second switching means connected in series with said resistor; said switching means connected in parallel with the series connection of said resistor and said second switching means, and operating means connected to said switching means and said second switching means for first opening said switching means and thereafter opening said second switching means.

2. The interrupter of claim 1 wherein said second switching means is normally open; said operating means being constructed to close said second switching means before opening said switching means.

3. The interrupter of claim 1 wherein said operating means opens said switching means in the vicinity of a current zero.
